(57) **CLAIM**

The ornamental design for a mounting device for a helmet as shown and described.

DESCRIPTION

FIG. 1 is a perspective view from the front, bottom and right of a mounting device for a helmet showing my new design; FIG. 2 is an exploded view of the mounting device for a helmet shown in FIG. 1, viewed from the rear, in which two components of the mounting device have been separated; FIG. 3 is a front plan view thereof; FIG. 4 is a rear plan view thereof; FIG. 5 is a top plan view thereof; FIG. 6 is a bottom plan view thereof; FIG. 7 is a right side plan view thereof; FIG. 8 is a left side plan view thereof; and, FIG. 9 is a reference view showing an illustrative environmental state of use of the mounting device for a helmet. The broken lines shown in FIG. 9 depict an illustrative environmental structure including a helmet, a mouth shield, a mouth shield holding device and a user's face that form no part of the claimed design.
